Inventor:

UNITED STATES PATENT OFFICE.

THOMAS E. CALVERT, OF CHICAGO, ILLINOIS; CORA HARDY CALVERT, EXECUTRIX OF
SAID THOMAS E. CALVERT, DECEASED.

SPLICE-BAR FOR RAILWAY-RAILS.

1,280,390.

Specification of Letters Patent.

Patented Oct. 1, 1918.

Application filed April 22, 1916. Serial No. 92,920.

To all whom it may concern:

Be it known that I, THOMAS E. CALVERT, a citizen of the United States, residing at Chicago, in the county of Cook and State 5 of Illinois, have invented certain new and useful Improvements in Splice-Bars for Railway-Rails; of which the following is a specification.

The object of this invention is to provide 10 improvements in splice-bars, commonly known as angle bars or fish plates, such as are used in forming the joints between adjacent lengths of railway rails.

In splice bars as heretofore constructed 15 the lower fishing surface, or contacting area, is of considerably greater extent than the upper fishing surface or contacting area, so that the wear on the upper surface takes place at a relatively rapid rate, whereby the 20 upper part of the bar is drawn in toward the web of the rail more than the lower part thereof, which results in a tilting of the splice or angle bar from a vertical position with a consequent less efficient operation of 25 the bar in supporting the rails at the joint.

It is one of the objects of this invention to 30 provide a splice bar having upper and lower fishing or wedging surfaces, which are approximately equal in area, in combination with securing bolts located in a novel manner so that the pressure per unit area on each of the wedging surfaces is approximately the same. By means of this construction the 35 angle bar is maintained in a substantially vertical position between the head and base of the rail.

A further object is to provide an angle bar 40 having upper and lower wedging surfaces of approximately equal area, and having an enlarged head which increases the effective resistance of the bar under stress. Still another object is to provide a splice bar having an enlarged head and a foot portion which is relatively thin from the web of the bar 45 outwardly, thereby providing clearance for the turning of the nuts used on splice bolts, and which is then enlarged in a novel manner to increase the strength of the bar and to effect a more efficient operation of the 50 spike and a decreased wear thereon. Still a further object is to provide an angle bar having a foot portion of novel form which allows the spike used to fasten the rail to the ties to penetrate the tie the greatest prac-

ticable distance, while at the same time presenting an enlarged surface of wear on the spike.

These and other objects of the invention will be set forth more clearly in the following specification, taken in connection with the accompanying drawings, in which one embodiment of the invention is illustrated.

In the drawings—

Figure 1 is a vertical section through the rail joint, showing my improved splice bars 55 in operative position with respect to the rail; and

Fig. 2 is a perspective view of the improved splice bar.

The usual railway rail 10 comprises a head 10^a, a web 10^b, and a base 10^c, all of which are of usual form and serve as a basis for showing the construction and advantages of this invention.

Between the head and base of the rail, on opposite sides of the web thereof, are the splice or angle bars 11, both of which are constructed according to the principles of my invention. Each angle bar comprises a head 12, web 13, and foot 14, the web being 65 provided with a plurality of bolting apertures 15, which are engaged by the bolts 16 passing through corresponding apertures 10^d in the web of the rail. Spring washers 17 are carried by these bolts, and nuts 18, engaging the bolts, provide means for drawing the angle bars toward each other and toward the web of the rail, so as to effect a tight wedging engagement of the angle bars between the head and base of the rail. Each 70 angle bar constructed according to the principles of this invention has an upper wedging surface 19 which contacts with the under surface of the head of the rail, and a lower wedging surface 20 which contacts with the upper surface of the base of the rail. The surface 19 extends between the longitudinal boundaries 21 and 22, while the lower wedging surface 20 extends between the boundaries 23 and 24. The boundaries 22 and 24 of the wedging surfaces are located 75 relatively close to the web 10^b of the rail, so that the fishing surfaces bear on the corresponding surfaces of the rail adjacent the web, and thereby provide a more rigid support for the rail than would be possible if the bearing surfaces terminated farther from the web of the rail.

It will be seen that by means of the above construction the lower wedging surface 20 has substantially the same area as the upper wedging surface 19, but it is preferable 5 to make the lower wedging surface somewhat larger in area than the upper wedging surface, and the lower surface is therefore made slightly greater in width than the surface 19. Since the wedging or fishing 10 surfaces are approximately equal in area, the wear on the upper and lower surfaces will take place at substantially the same rate, so that after continued use of the angle bar, and after tightening of the nuts 18 on 15 the bolts 16, the angle bars will be maintained with their lateral surfaces 11^a in substantially vertical planes, as when first adjusted on the rail.

In order to secure the operation of the 20 splice bars as above described, the bolting apertures 15 are located so that their center lines 25 are below what has hitherto been considered the proper position for the center lines of the bolting apertures, so as to 25 equalize the pressure of the bolts on the upper and lower wedging surfaces, whereby the pressure per unit area on those surfaces will be uniform. However, since it is desirable to make the lower wedging surface of slightly 30 greater extent than the upper wedging surface, the center lines of the bolting apertures are located slightly below the line 26, which is midway between the horizontal planes 27 passing through the longitudinal 35 center lines of the wedging surfaces, the location of these last-named center lines being indicated by the transverse lines 28. Thus a relatively greater portion of the pressure exerted by the bolts is placed upon 40 the lower wedging surfaces of increased area, thereby securing a uniform pressure per unit of area.

The location of the bolts 16, below the positions previously occupied by similar 45 fastening means, makes it possible to place an increased quantity of metal in the head 12 of the angle bar, thereby increasing the resistance of the bar to the stresses exerted upon it. In the form of the invention 50 shown in the drawings the head is enlarged inwardly from the web 13, as shown at 12^a, the inner surface 12^b of the head being spaced from the web 10^b of the rail, and the lower surface 12^c being spaced, preferably, from the bolts 16. The outer surface 55 of the splice bar inclines downwardly from the rail head, as shown at 12^d, from the boundary 21 of the upper wedging surface to the vertical surface 11^c of the angle bar. 60 It will be observed that the web 13 is located outwardly from the web of the rail a considerable distance, the outer surface being spaced outwardly from the lateral edge of the rail head, so that a relatively great enlargement of the head of the angle bar is 65

permitted inwardly of the web, thereby effecting the concentration of a large portion of the metal of the bar as far as possible from the center of gravity and neutral axis of the bar. At the lower end of the web 13, 70 the foot 14 of the angle bar projects inwardly, as shown at 14^a, in order to extend the lower wedging surface inwardly as far as possible toward the web of the rail. The upper wedging surface is preferably made 75 as large as possible, and the lower wedging surface—of substantially equal area—is arranged to occupy substantially similar position with respect to the web of the rail, thereby securing a more rigid support of 80 the rail joint, as above pointed out.

From the boundary 23 of the lower wedging surface, the lower surface of the foot 14 of the angle bar inclines upwardly and outwardly away from the rail, as indicated by 85 the line 30—30, which diverges from the plane 31—31 of the upper surface of the rail base. This inclined portion of the under surface of the angle bar terminates along the boundary 32, and from this boundary 90 outwardly the portion 33 of the under surface of the angle bar lies substantially parallel to the plane 31—31 of the upper surface of the rail base. The parallel portion 33 of said under surface terminates at the 95 downwardly extending shoulder 34, which is located outwardly from the edge of the rail base and which is formed on the enlarged flange 35 which extends along the lateral edge of the angle bar. This construction permits the formation of a lower 100 wedging or fishing surface having an area substantially equal to that of the upper wedging surface and brings the lower bearing of the angle bar nearer the web of the rail where the bearing is most rigid, while 105 at the same time preventing a decrease in the strength of the angle bar.

The foot of the angle bar is relatively thin from the web outwardly to the point 110 36, where it is engaged by the under surface of the head 37^a of one of the rail spikes 37, which pass through spiking slots or apertures 38 formed in the angle bar along the lateral edge thereof. This relatively 115 thin portion of the foot is preferably of substantially the same thickness as the web 13 thereof, and it serves to permit the turning of the nuts 18 on the bolts 16, which occupy positions relatively close to the foot 120 portions of the angle bars as compared with other forms of angle bars heretofore used. For instance, if the nuts 18 are square in cross section, they will during the turning thereof occupy extreme positions, as indicated by the dotted lines 18^a, so that if the foot portions of the angle bars were relatively thick the necessary adjustment of the nuts on the bolts would prevent the location of the bolting apertures in the manner 125 130

described to effect a uniform pressure per unit of area upon the wedging surfaces of the angle bars and rail.

From the outer boundary 36 of the relatively thin portion of the foot, the angle bar is increased in thickness, so that the upper surface 38^a thereof makes a lesser angle with the horizontal than the upper surface 39 of the relatively thin portion adjacent the web of the angle bar. The metal which is placed in the foot, beneath the surface 38^a, has heretofore been placed in the innermost part of the foot of the angle bar, which in this construction is made relatively thin, and it will be seen that the location of this metal above the plane 39^a of the surface 39 operates to increase the thickness of the flange 35 along the lateral edge of the angle bar, thus forming a thickened rib 20 in a location which is removed as far as possible from the center of gravity and neutral axis of the angle bar. In addition to providing a great increase in strength, the formation of the enlarged rib or flange 35 serves to increase the area of contact of the angle bar with the rail spikes, so that the wear on the spikes while preventing lengthwise movement of the rail will be decreased, and the length of service thereof correspondingly increased. By making the portion of the foot 14 inwardly of the edge of the rail base relatively thin, it is possible to have the spikes penetrate the ties a greater distance than with the other forms of angle bars previously in use, so that the holding power of the splice is increased, and the lateral bending moment on the spikes, exerted by the lateral pressure of the rails, is correspondingly decreased.

From the foregoing description it will be apparent that by providing an enlarged head 12 and an enlarged flange 35 along the lateral edge of the foot of the bar, a relatively large portion of the metal in the bar is concentrated in parts which are relatively distant from the center of gravity of the bar, whereby the resistance of the bar to the stresses exerted upon it is greatly increased, as will be apparent to those skilled in the art. The provision of upper and lower wedging surfaces of approximately equal area, in combination with bolting apertures so located that the bolts passing therethrough will exert substantially

equal pressures per unit of area upon the upper and lower wedging surfaces, makes it possible to maintain the splice bar in a substantially vertical position, even after continued use, so that it will at all times provide the most efficient support for the railway rails which are united by it at a joint. The reduced area of contact 20-23 should enable the manufacturers to maintain in rolling a more accurate fit than with the very much greater contact surface 65 ordinarily used.

Although I have shown a particular embodiment of the invention for purposes of illustration, it will be understood that it may be embodied in other forms without departing from the scope of the invention as defined in the appended claims.

I claim:-

1. A railway rail splice bar of angle-shaped cross section having a web and a head above said web which is enlarged on the side toward the web of the rail to which the splice bar is attached, said bar having a foot member which is of substantially the same thickness as the web of the bar from the web of the rail outwardly to a point adjacent to the edge of the rail base, from which point outwardly the foot portion of the bar is thickened by forming its upper surface with a lesser angle to the horizontal than the upper surface of the portion thereof nearer the web of the rail.
2. A railway rail splice bar having a foot portion which contacts with the base of the rail adjacent the web of the rail and which is then spaced from said base outwardly of said rail, the lower surface of said foot portion terminating in a longitudinal downwardly extending shoulder spaced outwardly from the edge of the rail base, said foot portion being relatively thin above said rail base and being enlarged on its side adjacent its outer edge by forming its upper surface with a lesser angle to the horizontal than the upper surface of the portion thereof nearer the web of the rail.

In testimony whereof, I have subscribed my name.

THOMAS E. CALVERT.
